UNITED STATES PATENT OFFICE.

ERIC HERMAN ERICSON, OF OSCARSHAMN, SWEDEN.

CANE-GUN.

SPECIFICATION forming part of Letters Patent No. 610,675, dated September 13, 1898.

Application filed October 30, 1897. Serial No. 656,979. (No model.)

To all whom it may concern:

Be it known that I, ERIC HERMAN ERICSON, a subject of the King of Sweden and Norway, and a resident of Köpmansgatan, 301, in the 5 city of Oscarshamn, in the Kingdom of Sweden, have invented a new and useful Improvement in Gun-Canes, of which the following is a specification, reference being had to the drawings accompanying and forming a part of 10 the same.

This invention relates to improvements in gun-canes where that part of the handle containing the breech-block is slideable out to one side from the barrel or breech of the same.

15 The object of the invention is to provide a gun-cane that shall be simple, cheap, and reliable and at the same time be available for use as a field-glass after the insertion of suitable lenses in place of the cartridge.

20 The invention consists principally in constructing the handle part which contains the breech-block so that it may be first drawn out to one side from the barrel and thereupon may be turned backward, so as to lie alongside 25 the barrel while the gun is to be loaded or while it is to be used as a field-glass.

The invention further consists in the particular construction and combination of parts, as hereinafter described and claimed.

30 In the accompanying drawings, Figure 1 shows a longitudinal section of the handle end of a gun-cane according to this invention with the breech-block closed, and Fig. 2 shows the same when open. Fig. 3 is an end 35 view of the same.

At the handle end of the barrel (the cartridge-chamber) a socket *a* is screwed on, which socket is provided with a side projection *b*. This projection *b* is in its turn provided with an oblong hole or slot *b'*, in which 40 runs a pin *d* or the like, going through the said slot and being fastened to the handle *c*. Behind the barrel the socket *a* is open toward the handle, while at the inner surface of its 45 three other sides there is provided a groove *a'*, in which a corresponding edge or guide *c'* of the handle fits in such a manner that the handle is movable to and from the barrel at about a right angle, thus forming the breech-block of the gun. The length of the slot *b'* is 50 such that when the handle has moved so far from the barrel that the pin *d* is in the outer

end of the slot *b'*, as shown in Fig. 2 by full lines, the guide *c'* has come out of engagement with the corresponding slot *a'* in the 55 socket *a*, in which case the handle can be turned about the pin *d*, so as to take up the position shown in Fig. 2 by dots and dashes. The extractor *e* is in the form of a two-armed lever and pivoted in a groove in the said projection *b* in such a manner that when the handle is turned about the pin *d* the end of the inner lever-arm of the said extractor catches the edge of the cartridge, while the outer arm is so arranged that it will be pressed down 60 by a shoulder *c²* of the breech-block when the handle is alongside the barrel, so that the first-mentioned arm of the extractor will draw out the empty cartridge.

By making the end of the extractor *e* with 70 which the shoulder *c²* engages in the shape of a spring, so that it will yield a little when the shoulder *c²* commences to press upon the same, the cartridge will be thrown out with greater force than otherwise would be the 75 case. The said springy end of the extractor also serves the purpose of rubbing hard against the part *c³* of the handle in order to produce so much resistance against the drawing out of the handle that the same will not 80 be liable to move out when not wanted to do so.

The hammer *f* is at its free end provided with a hook *f'*, which grips about a corresponding projection *a²* of the socket *a*, so that 85 the hammer in its closed position prevents the handle from being drawn out. The turning of the handle alongside the barrel also makes the insertion of cartridges easier than is the case when the handle is only drawn out 90 sidewise and makes the discharging of the gun while loading less liable to occur.

I am aware that it is not new to arrange the breech-block and part of the handle to be slid out sidewise and turned backward and I 95 do not claim this.

What I claim, and desire to secure by Letters Patent, is—

In a gun-cane, a handle and breech-block fastened to the barrel, by means of a pin running in a slot in a part of the handle fixed to the barrel, and suitable to be turned parallel with the barrel, a cartridge-extractor shaped as a two-armed lever pivoted to the said fixed 100

part of the handle, and a shoulder on the
movable part of the handle adapted to engage
with one end of the said cartridge-extractor
when the handle and breech-block is turned
5 alongside the barrel, substantially as and for
the purpose set forth.

In testimony that I claim the foregoing as

my invention I have signed my name, in pres-
ence of two witnesses, this 12th day of June,
1897.

ERIC HERMAN ERICSON.
